(57) **CLAIM**

The ornamental design for a lavatory basin, substantially as shown and described.

DESCRIPTION

FIG. 1 is a front, raised perspective view of a lavatory basin according to the invention;

FIG. 2 is a front view of the lavatory basin according to FIG. 1;

FIG. 3 is a rear view of the lavatory system according to FIG. 1;

FIG. 4 is a left side view of the lavatory system according to FIG. 1;

FIG. 5 is a right side view of the lavatory system according to FIG. 1;

FIG. 6 is a top view of the lavatory system according to FIG. 1;

FIG. 7 is a bottom view of the lavatory system according to FIG. 1; and,

FIG. 8 is a cross-sectional view of the lavatory system according to FIG. 6 taken along line **8-8**.

The broken lines shown in the drawings form no part of the claimed design. The surface shading illustrated in the drawings is provided merely to highlight the contour of the design and is not part of the claimed design. All surfaces not shown form no part of the claimed design.

1 Claim, 7 Drawing Sheets
